VEHICLE MILK TANK OR THE LIKE

Robert T. Silvis, 335 Springfield Ave., South Beloit, Ill.

Filed Mar. 25, 1960, Ser. No. 59,872

Term of patent 14 years

(Cl. D23—1)

Fig. 5

Fig. 2

Fig. 1

Fig. 3

Fig. 4

Fig. 6.

Fig. 7.

FIG. 1 is a view in perspective of a vehicle milk tank showing my new design;

FIG. 2 is a front elevational view;

FIG. 3 is a side elevational view;

FIG. 4 is a rear elevational view;

FIG. 5 is an enlarged view of one of the rear upper tail lights as seen in FIG. 1.

FIG. 6 is a top plan view;

FIG. 7 is a side elevational view from the opposite side of FIG. 3.

I claim:

The ornamental design for a vehicle milk tank or the like, as shown.
